UNITED STATES PATENT OFFICE.

NICHOLAS WITSCH, OF JERSEY CITY, NEW JERSEY, ASSIGNOR TO THE AMERICAN LITHOGRAPHIC COMPANY, OF NEW YORK, N. Y.

DESIGN FOR A CIGAR-BOX COVER.

SPECIFICATION forming part of Design No. 25,454, dated May 5, 1896.

Application filed March 11, 1896. Serial No. 582,824. Term of patent 7 years.

To all whom it may concern:

Be it known that I, NICHOLAS WITSCH, a citizen of the United States, residing at Jersey City, in the county of Hudson and State 5 of New Jersey, have invented and produced a new and original Design for an Ornamental Print or Pattern for Cigar-Boxes; and I do hereby declare the following to be a full, clear, and exact description of the same, reference 10 being had to the accompanying drawing, forming a part thereof.

The design is placed upon the cigar-box, as shown in the drawing. It contains the figure of a woman dressed in bloomers riding a bicycle on a roadway, cut flowers strewn in the 15 roadway upon each side of the bicycle, and a landscape view in background.

I claim—

The design for an ornamental print or pattern for cigar-boxes, substantially as shown 20 and described.

In testimony whereof I affix my signature in presence of two witnesses.

NICHOLAS WITSCH.
